JOHN L. POLAND, OF WAUNETA, KANSAS.

SAFETY APPLIANCE FOR CARBUREETERS.

1,314,900.

Specification of Letters Patent. Patented Sept. 2, 1919.

Application filed February 20, 1918. Serial No. 218,288.

To all whom it may concern:

Be it known that I, JOHN L. POLAND, a citizen of the United States, residing at Wauneta, in the county of Chautauqua and State of Kansas, have invented certain new and useful Improvements in Safety Appliances for Carbureters, of which the following is a specification.

The primary intention of the present invention is to prevent unauthorized appropriation of motor vehicles, such as are propelled by internal combustion engines utilizing liquid fuel.

The purpose of the invention is to combine with the carbureter means for locking the controlling valve after the latter has been turned so as to shut off the flow of fuel to the carbureter and engine.

The invention furthermore aims to provide means whereby any carbureter in use may be rendered safe, thereby guarding against theft, or unauthorized use of a pleasure car or other motor-driven vehicle.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

In the drawings:

Figure 1 is an elevation of a carbureter of conventional type provided with safety means embodying the invention.

Fig. 2 is a sectional detail of the lock mechanism and controlling valve.

Fig. 3 is a detail section on the line 3—3 of Fig. 2.

Corresponding and like parts are referred to in the following description and indicated in the several views of the drawings by like reference characters.

The numeral 1 designates a carbureter of any approved type or design such as commonly employed in connection with internal combustion engines for vaporizing liquid fuel. The numeral 2 indicates the feed pipe which conveys the liquid fuel from a source of supply to the carbureter. In accordance with the present invention, a combined cut-off valve and lock is interposed between the feed pipe 2 and the carbureter, and is attached to the carbureter in any way to form practically a part thereof. When adapting the invention to carbureters in the course of

manufacture, the combined valve and lock casing will be constructed as a part of the carbureter, and when adapting the invention to a carbureter in use or on the market, the casing of the controlling valve and lock mechanism will be brazed, welded, or otherwise connected to the body of the carbureter so as to be practically inseparable therefrom.

The casing for the valve and lock mechanism is indicated by the numerals 3 and 4, said parts being indicated for convenience as being separable to admit of ready assemblage of the coöperating parts. A plug valve 5 is mounted in an opening formed in the casing 3 and its projecting end is constructed to receive a key by means of which the same may be turned. The casing 4 is formed with a recess 6 which receives the lock mechanism, the same comprising a key-operated barrel 7 and a plurality of tumblers 8 which are shown as of the lever type and pivotally mounted upon a pin 9. The tumblers 8 have their free ends bent and adapted to extend through an opening 10 formed in the side of the casing 3 adjacent the recess side 6 of the casing 4. The valve 5 is provided in its side with an opening or recess 11 to receive the active ends of the tumblers 8 whereby the valve is locked when turned to shut off the flow of fuel to the carbureter. The casing elements 3 and 4 are adapted to be connected in any manner to prevent their ready separation after being assembled thereby guarding against tampering with the lock mechanism.

It is to be understood that a lock mechanism of any design may be utilized, and that such lock mechanism may comprise any number of tumblers depending upon the security to be obtained and the cost of the safety appliance. The form of lock mechanism illustrated is preferred because of its extreme simplicity and the minimum number of parts embodied in its organization.

In practice, when the valve 5 is turned into open position to admit of the fuel passing freely from the source of supply to the carbureter, the motor vehicle may be operated when necessary, but when it is desired to secure the advantages of the invention, the valve 5 is turned by means of a suitable key, not shown, so as to cut off the supply of fuel to the carbureter, and when the valve is thus positioned, the recess or opening 11 is brought in position to register with the active ends of the tumblers 8 and the latter are

projected into engagement with the valve 5 and secure the same against unauthorized operation, thereby preventing unauthorized appropriation of the motor vehicle. It will 5 thus be understood that a pleasure car or other type of motor vehicle may be left standing with reasonable safety because the fuel controlling valve is locked and may not be turned into open position except by 10 proper use of predetermined keys, one for the lock and the other for the valve.

What I claim is:

1. A carbureter having as a part of the body thereof a lock controlled opening to 15 prevent the passage of fuel therethrough.

2. A carbureter and a lockable fuel controlling valve forming a part of the body thereof to prevent the passing of fuel therethrough.

3. A carbureter, a valve forming part of the body thereof and disposed adjacent the fuel intake, and a key operated lock for the valve forming substantially a part of the carbureter body.

In testimony whereof I affix my signature 25 in presence of two witnesses.

JOHN L. POLAND.
